UNITED STATES PATENT OFFICE

166,403

SLINGSHOT

Harold D. McColl, Douglas, Wyo.

Application December 21, 1951, Serial No. 17,796

Term of patent 14 years

(Cl. D34—15)

To all whom it may concern:

Be it known that I, Harold D. McColl, a citizen of the United States of America, residing at Douglas, in the county of Converse, and State of Wyoming, have invented a new, original, and ornamental Design for a Slingshot, of which the following is a specification, reference being had to the accompanying drawings, forming a part thereof, in which

Fig. 1 is a perspective view of a slingshot, showing my new design, and

Fig. 2 is a side elevational view thereof, looking from the right of Fig. 1.

The side opposite that shown in Fig. 1 is the same as that illustrated with, however, the design features in relatively reverse position, as indicated by the outline of the slingshot.

The essential features of my design are shown in full lines.

I claim:

The ornamental design for a slingshot, as shown and described.

HAROLD D. MCCOLL.
